UNITED STATES PATENT OFFICE.

CHARLES J. LEHMANN, OF HAMILTON, OHIO, ASSIGNOR TO THE BRUNHOFF MANUFACTURING COMPANY, OF SAME PLACE.

DICE-SHAKER.

SPECIFICATION forming part of Letters Patent No. 632,270, dated September 5, 1899.

Application filed November 10, 1898. Serial No. 696,024. (No model.)

To all whom it may concern:

Be it known that I, CHARLES J. LEHMANN, a citizen of the United States, residing at Hamilton, in the county of Butler and State of Ohio, have invented certain new and useful improvements in Dice-Shakers, of which the following is a specification.

My invention relates to improvements in dice-shakers.

10 One of its objects is to provide reliable and simple mechanism for shaking or throwing the dice in an inclosing case.

Another object is to provide mechanism for imparting a compound vibration to the platform upon which the dice rest, which results in the thorough shaking or throwing of the dice.

15 The invention also consists in certain details of construction and arrangement, all of which will be more fully set forth in the description of the accompanying drawings, forming part of this specification, in which—

Figure 1 is a central vertical section through my improved dice-shaker. Fig. 2 is a section 25 on line $x-x$, Fig. 1. Fig. 3 is a perspective view, partly in section, showing the manner of vibrating the platform. Fig. 4 is a similar view to Fig. 3, showing the parts in another position.

30 A represents the frame of the shaker, and B a glass dome hinged thereto.

The operative mechanism consists of a platform or disk C, provided on its under side with a stem D, which passes through a hole 35 in the conical bracket E and through an opening in the end of the crank-arm F, which is mounted upon the end of a shaft G. This shaft G is rapidly rotated a number of times, first in one direction and then in the opposite 40 direction, by means of a train of gears H I J on the shafts G K, said train of gears being driven by means of a segment L on the end of a hand-lever M, the outer end m of which projects through the side of the case A.

45 N represents the pivot on which the lever M reciprocates, and O a spring to return the lever to its original or normal position.

P P' represent frame-pieces clamped together by screws $p p'$ and held to the frame 50 A by screws tapped into the ears a. These frame-pieces P P' serve to journal the shafts

G K and lever M and support the conical bracket E, which carries the vibrating disk.

R represents a lug or ear on the outside of frame A, against which the thumb or finger 55 rests in operating the lever M.

S represents a chamber formed by the dome B and platform C, within which the dice are thrown or shaken.

Referring to Figs. 3 and 4, it will be seen 60 that when at rest, Fig. 3, the disk or platform C is in a horizontal position. When the lever M is pressed, however, the shaft G and crank-arm F are turned several complete revolutions, in each of which the platform C, 65 on account of the engagement of its stem D with the crank-arm F, assumes a series of positions of different angles, of which Fig. 4 represents the maximum. It will also be noted that as the crank-arm F rotates the 70 plane in which the platform C is tilted continually changes and that the impulse imparted to the dice causes them to whirl or spin, thereby giving them a thorough shaking. As soon as the lever M is released the spring O revolves the shaft C in the opposite direction 75 until the parts have resumed their original position.

I believe I am the first to apply a compound vibration to the platform of a dice-shaker, 80 and I do not wish to limit myself to the particular mechanism employed to produce this result.

Having described my invention, what I claim is—

1. In a dice-shaker, a chamber to hold the dice consisting of a dome or cover and a vibrating platform, a stem projecting from the under side of said platform, a bracket forming a step bearing and support for said stem 90 and platform at a point close to the platform leaving the lower end of the stem free to be vibrated laterally in various planes, an actuating-lever and transmitting mechanism, substantially as specified for vibrating said stem laterally, alternately in two or more different planes, substantially as specified. 95

2. In a dice-shaker, a chamber to hold the dice consisting of a dome or cover and a vibrating platform provided upon its underside 100 with a stem, a bracket forming a step bearing or support for said stem and platform at

a point close to the platform, leaving the lower end of the stem free to be vibrated, and lever and transmitting mechanism substantially as described for laterally vibrating the lower end of the stem, substantially as specified.

3. In a dice-shaker a chamber to hold the dice consisting of a transparent cover and a vibrating platform, a stem connected to the 10 under side of said platform, a conical bracket forming a step-bearing for said stem and platform, and lever mechanism substantially as specified for laterally vibrating the lower end of said stem in a series of different planes, 15 substantially as specified.

4. In a dice-shaker a dice-chamber consisting of a dome or cover and a vibrating platform, said platform being stepped and supported by means of a stem secured to the 20 underside thereof, in a bracket or frame piece, a shaft carrying a horizontally - revolving

crank-arm engaging the lower end of said stem to vibrate the platform, and means substantially as shown for revolving said shaft.

5. In a dice-shaker a vibrating platform 25 stepped and supported by means of a stem projecting from the under side thereof, upon a bracket or frame piece, a segment-lever held normally in a fixed position by means of a spring, transmitting - gears engaging and 30 transmitting motion from said lever to a shaft carrying a horizontally-revolving crank-arm, which engages the lower end of the platform-stem and vibrates the platform, substantially as specified.

In testimony whereof I have hereunto set my hand.

CHARLES J. LEHMANN.
